UNITED STATES PATENT OFFICE.

THEODORE WILLARD CASE, OF SCIPIO, NEW YORK.

ELECTRICAL DEVICE.

1,406,149.

Specification of Letters Patent. Patented Feb. 7, 1922.

Application filed January 22, 1918. Serial No. 213,229.

To all whom it may concern:

Be it known that I, THEODORE W. CASE, a citizen of the United States of America, and resident of Scipio, in the county of Cayuga, in the State of New York, have invented new and useful Improvements in Electrical Devices, of which the following, taken in connection with the accompanying drawings, is a full, clear, and exact description.

10 This invention relates to certain improvements in electrical devices adapted for many and various uses, and as merely illustrative of one such use I have illustrated the same as an amplifier and detector of changes in electro motive force in a primary circuit, which change may be due to variations in impedance in said circuit, either automatically or mechanically effected, as through resistance of light-reactive substances, or to other causes which it may be desirable to determine and translate.

15 In the drawings:

Fig. 1 is a diagrammatic illustration of apparatus of my invention.

20 Fig. 2 is a similar view of a slightly modified form of apparatus.

The invention comprises a primary circuit —1— containing a source of potential, as the battery —2—, and a resistance —3—, in this specific illustration being an automatically variable resistance such as may be produced by the use of a light-reactive or light-responsive cell, particular substances for such use being set forth in my copending applications, Ser. No. 195,652, patented July 8, 1919, No. 1,309,181, and Ser. No. 195,653, filed October 9, 1917.

25 The primary circuit may embody, as shown in Figure 1, a small diameter wire —4—, which may be a fine silvered or platinized quartz fibre, extending through a vacuum tube or vessel —5—. A suitable magnetic field with lines of force crossing or intersecting the wire or fibre —4— is produced in any practical way, as by a magnet —6— and preferably the lines of force cut the conductor —4— at substantially right angles to the conductor. Sealed within the vacuum vessel is an electrode —7—, in this illustration taking the form of a filament adapted to be electrically heated from a suitable source, as by battery —8— connected across the terminals of the filament.

30 A secondary circuit —9— constituting a measuring or translating circuit and containing a suitable source of E. M. F., as battery —10—, and a suitable indicating device

—11— which may be a galvanometer, telephone receivers, or the like, is suitably connected to one terminal of the filament and to the wire or fibre —4—.

The vacuum in the vessel should be adjusted or fixed empirically to render the apparatus as sensitive as possible.

The operation of the apparatus is as follows:

The filament is heated by the E. M. F. from battery —8— and this filament circuit may contain a mechanically variable resistance to control the extent of heating of the filament. Any change in the amount of current flowing through the primary circuit —1— will cause a deflection of wire —4—, either toward or from the heated filament, due to the magnetic field produced by magnet —6—.

Deflection of the wire toward or from the filament affects the amount of current flowing from the wire to the filament and as the wire can be adjusted with respect to the filament at such a point that any deflection of the wire causes a marked increase or decrease in the current flowing from the wire to the filament, minute changes of E. M. F. in the circuit —1— will result in materially increased changes in the current flowing through circuit —9— to such an extent that they may be easily detected, measured or translated, as desired.

The variation in E. M. F. in circuit —1— may be affected by varying the intensity of the light rays to which the light reactive cell —3— is subjected, or, as stated, a mechanically variable resistance may be used in said circuit, or any change in E. M. F. in said circuit due to any cause may be detected, measured and translated.

In Figure 2, I have disclosed an apparatus of similar character except that the wire —4— is omitted and the vacuum maintained in the vessel is so correlated with the E. M. F. of circuit —1— that a constant stream of electrons flows between the terminals of said circuit positioned within the vacuum tube —5—, and this constant stream of electrons upon variations of the current in primary circuit —1— is deflected toward and from the heated filament —7— under the influence of the magnetic field described in the same manner as wire —4— and with the same effect.

Otherwise, the operation of the two devices is the same.

It will be understood that the magnetic

field may be produced in various ways, the apparatus in this specific particular being similar to the Einthoven galvanometer and that the magnet or the magnetic field producing means may be arranged in various ways to produce a magnetic field of desired character with lines of force preferably at substantially right angles to the conductor or path of electron discharge or travel and 10 variations may be made in the details of construction and operation of the apparatus, all within the scope of the appended claims.

What I claim is:

1. In combination, a vacuum vessel, a magnetic fibre traversing the vessel, an electrode sealed within the vessel, means for heating the electrode, and a magnetic field with lines of force intersecting the fibre for deflecting the fibre with relation to said 15 electrode.
2. A circuit including a fibre, means for varying the current flowing in said circuit, an electrode, means for heating the electrode and a second circuit connecting across the 20 electrode and the fibre and containing an indicating device.
3. In combination, a vacuum vessel, a current path traversing the vessel, an electrode sealed within the vessel, means for heating 25 the electrode, and a magnetic field with lines of force intersecting the current path for deflecting the current path with relation to said electrode.
4. In combination, a vacuum vessel, a current path traversing the vessel, a circuit, including said current path, means for varying 30 the current flowing in said circuit, an electrode sealed within the vessel, a second circuit connected across the electrode and the 35 current path and a magnetic field with lines of force intersecting the current path.
5. In combination, a current path, a circuit including said current path, a source of potential and a variable resistance in said 40 circuit, a magnetic field with lines of force intersecting the current path, an electrode adjacent the current path, a second circuit connected across the electrode and the current path, said second circuit including a 45 source of potential and an indicating device.
6. In combination, a current path, a circuit including said current path, means for varying the current flowing in said circuit, an electrode adjacent the current path, means for heating the electrode, and a second 50 circuit connected across the electrode and the current path, and containing a source of potential and an indicating device.
- 60 7. In combination, a vacuum vessel, a current path traversing the vessel, a circuit including said current path, said circuit containing a source of potential and a variable

resistance, an electrode sealed within the vessel, means for heating the electrode, a 65 circuit connected across the electrode and the current path, said circuit including a source of potential and an indicating device, and a magnetic field for lines of force intersecting the current path. 70

8. In combination, a vacuum vessel, a circuit including a current path located within the vessel, a source of potential and a variable resistance in said circuit, a magnetic field having lines of force intersecting the current 75 path, an electrode sealed in said vacuum vessel and projecting into the interior thereof at substantially right angles to the current path, means for heating the electrode and a circuit connected across the electrode 80 and the current path and containing a source of potential and an indicating device.

9. In combination, a vacuum vessel, a circuit including a small diameter conductor sealed in said vessel, a source of potential and a variable resistance in said circuit, a magnetic field having lines of force intersecting the conductor, an electrode sealed in 85 said vacuum vessel, means for heating said electrode, and a circuit connecting said electrode and said small diameter conductor and containing a source of potential and an indicating device. 90

10. In combination, a vacuum vessel, a circuit including a current path located within the vessel, a source of potential and a light reactive element in said circuit, a magnetic field having lines of force intersecting the current path, an electrode sealed in said vacuum vessel and projecting into the interior thereof at substantially right angles to the current path, means for heating the electrode and a circuit connecting said electrode and said current path and containing a 95 source of potential and an indicating device. 100

11. In combination a vacuum vessel, a circuit, including a small diameter conductor located within the vessel, a source of potential and a light reactive element in said circuit, a magnetic field having lines of force intersecting the small diameter conductor, an electrode sealed in said vacuum vessel and projecting into the interior thereof at substantially right angles to the small diameter conductor, means for heating the electrode and a circuit connecting said electrode and said small diameter conductor and containing a source of potential and an indicating device. 115

In witness whereof I have hereunto set 120 my hand this 4th day of January, 1918.

THEODORE WILLARD CASE.
